(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a display screen or portion thereof with graphical user interface showing our new design.

The peripheral dashed broken lines depict a display screen or portion thereof, and form no part of the claimed design. The black solid lines form part of the claimed design, and the faded portions within the black solid lines depict user defined content which forms no part of the claimed design. Typography forms part of the claimed design. The horizontal dotted line within the peripheral dashed broken lines forms no part of the claimed design. The faded portion below the horizontal dotted line forms no part of the claimed design.
